UNITED STATES PATENT OFFICE.

ELMER E. PHINNEY, OF MIDDLEBOROUGH, AND JOHN J. FALVEY, OF BOSTON, MASSACHUSETTS.

DESIGN FOR A BICYCLE-BOOT.

SPECIFICATION forming part of Design No. 27,771, dated October 19, 1897.

Application filed August 26, 1897. Serial No. 649,646. Term of patent 7 years.

To all whom it may concern:

Be it known that we, ELMER E. PHINNEY, of Middleborough, in the county of Plymouth, and JOHN J. FALVEY, of Boston, in the county of Suffolk, State of Massachusetts, have invented and produced a new and original Design for Bicycle Boots or Leggings, of which the following is a specification, reference being had to the accompanying drawing, forming a part thereof.

The drawing shows in side elevation our newly-designed bicycle boot or legging.

As shown in the drawing, the leading or material feature of our design consists in elongated panels at the calf of the leg portion of the boot and elongated panels at the front top of the boot.

The leg portion *a* of the boot, or it may be of a legging, is represented as closed at the front by lacings. Along the middle of the

back of the leg portion a narrow strip *b* appears, and at each side of it at the widest part of the leg portion an elongated panel *c* appears, the contour of which may be more or less ornamental, if desired. At the front side ²⁵ of the leg portion panels *d* appear, they being likewise elongated, and their contour may be also more or less ornamented, if desired.

We claim—

The design for a bicycle boot or legging, as ³⁰ shown and described.

In testimony whereof we have signed our names to this specification in the presence of two subscribing witnesses.

ELMER E. PHINNEY.
JOHN J. FALVEY.
